UNITED STATES PATENT OFFICE.

HOMER J. POOLE AND STEPHEN E. COUCH, OF SPRINGFIELD, MASSACHUSETTS;
SAID COUCH ASSIGNOR TO SAID POOLE.

DEVICE FOR GRINDING CONTACT POINTS.

Application filed May 24, 1920. Serial No. 383,875.

To all whom it may concern:

Be it known that we, HOMER J. POOLE and STEPHEN E. COUCH, citizens of the United States of America, residing at Springfield, 5 in the county of Hampden and Commonwealth of Massachusetts, have invented certain new and useful Improvements in Devices for Grinding Contact Points, of which the following is a specification.

10 This invention relates to improvements in devices for grinding or trueing the contact points and the distributor buttons or plates of electrical ignition systems which are used for igniting the charge in internal combustion engines.

Broadly, the invention discloses the use of a base plate or receiving platform, adapted to be adjusted to any suitable height and for receiving the jig or block on which the 20 contact points are placed, whereby when the base piece or platform is moved upward, the contact points are brought against the surface of a grinding or trueing wheel. It is well known that the contact points are composed of very hard material, as tungsten 25 steel, which cannot be accurately trued with a file.

An object of the invention is to provide jigs for holding and receiving the fixed and 30 movable contact points of various ignition systems, as Delco, Atwater Kent, Ford, Remy, Connecticut, etc., but all capable of being used in connection with one common grinding wheel.

35 Referring to the drawings:

Fig. 1 is a plan view of the jig-receiving platform showing an electric motor, a grinding wheel, the upper surface of the platform, and in dotted lines the means for adjusting the platform.

40 Fig. 2 is a side elevational view of Fig. 1, showing the device as used, the wheel being shown in the act of grinding the contacts, also the means for accurately raising 45 and lowering the jigs.

Fig. 3 is a side elevational view partly in section on the line 3—3 of Fig. 1, showing clearly the manner of adjusting the front and rear edges of the supporting platform or plate.

50 Fig. 4 is a detail view of one of the jig blocks for receiving the fixed contact points of the make and break devices and the distributor button.

55 Fig. 5 is a perspective detail view of the jig device for receiving and holding the con-

tact points of the well-known Atwater Kent system.

Fig. 6 is a perspective detail view of the block or jig for holding the flexible plates to which the contact points of the Ford system are secured.

Fig. 7 is a detail view of the block or jig for receiving and holding the Connecticut system of ignition.

Fig. 8 is a detail view of the jig or block 65 for holding the Remy contact points.

Fig. 9 is the block for receiving and holding the contact points of the Delco system.

Referring to the drawings in detail: The base member on which the vertically adjustable plate is mounted, is indicated at 1. This member is provided at the front edge thereof with a threaded bolt 2, a nut 3 for raising or lowering the bolt, and the jig-receiving platform 4 to which it is attached at its 70 upper end, as indicated at 5. The rear edge of the plate 4 is pivotally connected to the two rods 6 as indicated at 4' and 4" which are formed with the openings 7 for receiving an adjusting pin 8, whereby the height 75 of the rods 6 and the plate 4 may be easily varied. The upper ends of these rods are connected to the plate 4 by means of the pintle 9 which passes through openings in the rods 6 and ears 10 on the plate. A suitable electric motor is indicated at 11, the shaft of which is shown at 12. To the outer end is secured the grinding wheel 13. This wheel is located in a suitable case 14 for purposes of protection, the casing being connected to the motor casing by means of arms 80 15. A suitable switch for turning the current on and off from the motor is indicated at 16.

Referring now to Fig. 4 which illustrates the jig or block for holding the contact 95 points and the distributor button while being ground. This block comprises the base portion 17, the integral upright member 18 formed with the threaded openings 19. These openings are for the purpose of receiving the usual fixed make and break contact points 20 against which the contact point of the usual movable arm strikes. This point is threaded into either one of the openings 19 and is locked in position by means 100 of the nut 21. 22 is an opening in the upright portion 18 for receiving the distributor button 23. To grind these points the jig or block 17 is placed on the adjustable platform 4, as shown in Fig. 3. The platform 110

is then raised to the desired height so that the points 20 and button 23 barely strike the periphery of the grinding wheel 13. The operator then moves the block 17 back and forth under the wheel by sliding the block on the platform 4. This platform is accurately raised or adjusted by means of the graduated nut 3. The amount that the wheel 3 is rotated is indicated by the pointer 24.

10 Referring now to Fig. 5 which is a jig or block having a platform portion 25, an upright member 26. In this member is an opening 27 to receive the contact point 28 which is to be ground and which is clamped in the opening 27 by means of the set-screw 29. The opposite end of the platform is formed with an upright member 30 having an inclined portion 31 and a ledge portion 32 in which is secured the threaded pin 33.

15 20 The spring contact plate indicated at 34 is placed on the portions 31 and 32. The U-shaped end 35 is placed over and against the pin 33. Also placed over this pin is the U-shaped piece 36 and the whole is then secured together by means of the nut 37. For the purpose of holding the contact point 38 in rigid position while being ground, a wedge shaped block 39 is slipped or pushed into the opening 40. The jig or block is now

25 30 placed on the adjustable platform 4 and the contact points 28 and 38 are ground in the manner already described. This jig structure is for receiving and holding the contact points of the Atwater Kent system.

35 Referring to Fig. 6, the jig or block is indicated as a whole by the numeral 41. It is formed with two upright portions 42 and 43. The portion 42 is formed with a flat surface 44 and two spaced block pieces 45 having the space 46 therebetween. 47 and 48 are upwardly extending pins to receive the openings 49 and 50 in the plate 51 on which is located the contact point 52. A plate 53 also fits over the pins 47 and 48 and a nut (not shown) is then threaded onto the pin 48 to retain the plate 51 rigidly in place on the block 42. For the purpose of attaching the other part of the make and break device, as indicated at 54, with the contact point 55 which is located on the spring plate 56, two upwardly extending threaded pins 55' are located on the upper end of the part 43 to receive the openings 57 of the plate 54, which is placed upon the upper surface 58 of the part 43 and between the spaced pieces 59 and secured in place by threading nuts onto the pins 55. The two contact points 52 and 55 may therefore be ground by placing the block or jig 41 on the adjustable platform 4 and then grinding them as already described. This jig is used for grinding the make and break points which are used for the Ford ignition system.

Fig. 7 shows a block or jig which is used

65 to grind the movable contact which is used

in the Connecticut system of electrical ignition. 60 designates the base part, 61 the upright having the opening 62 to receive the fixed contact point 63. 64 designates a U-shaped piece that is secured to the part 61 by means of the screws 65. 66 is a plate that is also secured to the piece 64. 67 is the usual arc-shaped piece which is placed on the pin 68 and the roller 68' in the recessed part 69. The contact points 63 and 70 are then ground as already described.

Fig. 8 represents the jig or block for grinding the contact points of the Remy system. 71 is the base-piece, 72 and 73 the integral upright portions. The portion 72 is formed with an opening 72' therein, for receiving the pin 73' of the arm 74. The part 74' of the arm rests in the recess 75 of the part 73 whereby the contact point 76 is rigidly held in place for grinding. The other contact point 78 is threaded into the opening 79 and then locked in place with the nut 80. The whole is then placed on the adjustable platform 4 for grinding.

Fig. 9 shows a jig or block for grinding the contact points of the so-called Delco system of ignition. 81 designates the base piece having the upwardly extending portions 82, 83, and 84. The portion 82 is provided with a pin 82' to receive the opening 85 of the breaker arm or lever 86 having the contact point 86' thereon. The arm 86 rests in the groove 87 of the part 82 which affords a solid and secure receptacle for the point 86' while being ground. The openings, 83', 83², and 83³ are for receiving the usual contact points and distributor buttons of other systems while being ground. The other arm 88 of this system is placed in the groove 89 of the part 84, and a pin is passed through the openings 84' and 84² to retain the arm in place. 90 designates a block that is placed in the space 91 and which rests in the notched recesses 92 to prevent the point 93 from being depressed or bent downwardly while being ground.

It will be seen from this description that we have produced a device or mechanism for accurately and rapidly grinding the make and break contact points of electrical ignition systems of various types or forms.

It should be observed that the upright or extension portions in which the contacts, distributor buttons, and the movable arm are placed, are all of substantially equal distances from the bottom of the base piece, whereby the grinding will be uniform on all of the contacts, buttons, and the contact on the movable arm. The contact part of the movable arm is directly and rigidly supported while being ground.

What we claim is:

1. A jig or block member for temporarily holding the contact points of an ignition system while being ground, said block com-

180

- prising a base-piece having a raised portion with openings therein to receive the usual fixed contact points and the distributor button, and another raised portion spaced from the fixed contact receiving portions and adapted to receive the movable member of the contact device.
2. A device for temporarily holding and retaining the contact points of an ignition system while being ground and comprising a block formed with spaced upwardly extending channeled portions to receive said points, as described.
3. A device for the purpose described comprising a base-portion with spaced integral uprights having openings therein to receive and retain the fixed contacts, and means including other uprights to receive the movable contact carrying members, whereby both of said contacts may be simultaneously ground while so held or retained.
4. A jig or block device for the purpose
- described, having recessed or grooved upwardly extending portions to receive a movable contact carrying arm, and pin devices 25 in the extension for retaining said arm in the grooved or recessed portions.
5. A jig or block device formed with a base piece and an upright or extension part having openings therein to receive and retain in place ignition contact points while being ground, as described.
6. A jig device for holding electrical contact points, distributor buttons and the contact point on the movable member of ignition systems while being ground, said device including a base-part and spaced extension pieces to receive the points, buttons, and movable member, said pieces being substantially an equal distance from the base-part, whereby the grinding operation will be of uniform character.

HOMER J. POOLE.
STEPHEN E. COUCH.
